DESIGN FOR A SPARK PLUG CLEANER

Fenick A. Vogel, West Caldwell, N. J., assignor to
The Oiljak Manufacturing Co., Inc., Montclair,
N. J., a corporation of New Jersey

Application October 2, 1946, Serial No. 133,692

Term of patent 3½ years

(Cl. D49—1)

To all whom it may concern:

Be it known that I, Fenick A. Vogel, a citizen of the United States, residing at West Caldwell, in the county of Essex and State of New Jersey, have invented a new, original, and ornamental Design for a Spark Plug Cleaner, of which the following is a specification, reference being had to the accompanying drawing, forming part thereof.

Fig. 1 is a perspective view taken from one side of a spark plug cleaner, embodying my new design;

Fig. 2 is a perspective view showing portions of the other side thereof.

I claim:

The ornamental design for a spark plug cleaner, substantially as shown.

FENICK A. VOGEL.
